UNITED STATES PATENT OFFICE.

CLEMENT RUSSELL, THOMAS H. RUSSELL, AND WILLIAM K. MILLER, OF MASSILLON, OHIO.

IMPROVEMENT IN THRASHING-MACHINES.

Specification forming part of Letters Patent No. 92,650, dated July 13, 1869.

To all whom it may concern:

Be it known that we, CLEMENT RUSSELL, THOMAS H. RUSSELL, and WILLIAM K. MILLER, of Massillon, in the county of Stark and State of Ohio, have invented certain new and useful Improvements in Thrashing-Machines; and we do hereby declare the following to be a full, clear, and exact description of the same, reference being had to the accompanying drawings, making a part of this specification, in which—

Figure 1 represents a perspective view from one side of the machine. Fig. 2 represents a perspective view from the opposite side, and Fig. 3 represents a vertical longitudinal section thereof.

Similar letters of reference, where they occur in the separate figures, denote like parts of the machine in all of the drawings.

Our invention relates, first, to certain mechanism for raising and lowering, and thus adjusting and holding, the concave under the thrashing-cylinder; and, secondly, it relates to the shielding of the gears, to protect them from the dust and grit, as well as to protect the attendants from accidents therefrom; and, finally, it relates to what is termed a "three-hitch" arrangement, in combination with the gear-supports, as will be hereinafter explained.

To enable others skilled in the art to make and use our invention, we will proceed to describe the same, with reference to the drawings.

A represents the mainframe of the machine, on which is supported a through-shaft, *a*, which has upon one of its ends a large cogged gear, *B*, that is incased, face and rim, by a cover, *C*, and upon the end of this through-shaft *a*, beyond the gear *B* and its cover, there is a half-coupling, *b*, which is protected by a cover, *c*, that is hinged to the case *C* at *d*, or it may be fixed rigidly thereto, if preferred, so that it will protect the coupling from dust and grit, and protect the workmen.

The gear-wheel *B* works into a pinion on the shaft or journal *e* of the thrashing-cylinder *D*, to run said cylinder; and this pinion is covered by a shield or cover, *f*, which, for the convenience of getting at said pinion, may be hinged.

The journal bearings or boxes *g* in which the shaft or cylinder journals run are sup-

ported on curved arms or brackets *E*, which extend outward from the main frame, to bring said bearings outside of the gears.

On the end of the shaft *a* opposite to that on which the gear *B* is placed, or on the opposite side of the machine from said gear, there is placed a bevel-gear, which is incased in a cover or shield, *F*; and into this bevel-gear there works another bevel-gear, *G*, also incased, as at *h*, said latter bevel-gear being on the end of a shaft, *i*, supported in outside bearings *j*, as seen in Fig. 2.

The half-coupling *b* makes one point at which the power to drive the thrasher may be applied.

The shaft *a* extends beyond the bevel-wheel it carries, as seen in Fig. 2, and is squared, so that the power may be applied at that end of the shaft, instead of the other end.

And, third, the shaft *i* is similarly squared, so that the power may be applied to it.

There are, therefore, three points to which the power that drives the thrashing-machine may be applied, from which fact the machine is termed a "three-hitch" machine.

The object and advantage in the "three-hitch" machine are this: That in thrashing in the field, which is the usual way, the machine is so set or placed as to throw the straw and chaff with the wind. If the wind blows against the machine, or against the free exit of the straw and chaff, the grain will not be thoroughly separated or cleaned. As the wind may change its direction at any time during the operation of thrashing, the thrashing-machine can be turned in a few moments' time to suit the direction of the wind, while to change the horse-power that drives it would be quite a laborious task. The "three-hitch" arrangement enables the thrasher to be turned and driven to suit the direction of the wind.

The concave *m* is pivoted to the frame at *n*; and the front of the concave is raised, lowered, adjusted, and held by a rack-lever, *o*, arranged upon one end of a shaft, *r*, said lever and shaft being held in any desired position by a pawl or dog, *s*, which takes into the rack or ratchet on said lever *o*, and there holds it in its set or adjusted position.

Upon the shaft *r* there are two cam-arms, *l*, which project into recesses *2* in the concave

or its frame, and the raising or lowering of the points of these cam-arms 1 raises or lowers the front end of the concave, where it is held by the dog *s*, as above stated.

The other portions of the thrasher not specially referred to in this specification are constructed and operate in the usual well-known way, and, being distinctly shown in the drawings, further description of them is not deemed necessary.

Having thus fully described our invention, what we claim therein as new, and desire to secure by Letters Patent, is—

1. The combination of the ratchet-lever and dog with the shaft and cam-arms, working in

connection with the hinged concave, for raising, lowering, adjusting, and holding said concave, substantially as described.

2. The shield or cover *c*, for shielding the joint in the coupling-rod, as set forth.

3. The three hitching-points *b*, *a*, and *i*, in combination with the driving-gear, arranged and supported substantially as herein described and represented.

CLEMENT RUSSELL.

THOS. H. RUSSELL.

W. K. MILLER.
